[57] ABSTRACT

A bayonet tube heat exchanger in which problems at the upper tube sheet created by high temperatures are eliminated. The bayonet tube assemblies are designed so that the heated secondary fluid which, having been heated in the space between the coaxial tubes in the lower portion of the bayonet tube assemblies, flows through the main tube sheet through a conduit which is inside of but spaced from the outermost of the coaxial tubes.

FIG. 2

BAYONET TUBE HEAT EXCHANGE**BACKGROUND OF THE INVENTION**

One type of heat exchanger which is presently being used in industry is the bayonet tube type. In the bayonet tube heat exchanger, the bayonet tube assemblies which carry the secondary fluid into indirect heat exchange with the primary fluid comprise two coaxial tubes. The outer tube has a closed end and the secondary fluid is flowed through the inner tube until it reaches the end of the bayonet tube assembly where it impinges against the closed end of the outer tube to reverse its direction and flow back in the annular space between the inner and outer tubes. It is when the secondary fluid flows between the inner and outer tubes that it picks up the greater part of the heat which is transferred to it by the primary fluid. The secondary fluid is collected between the tube sheet on which the outer tubes are mounted and another tube sheet which is connected to the ends of the inner tubes. There is a space between the tube sheets because the inner tubes are longer than the outer tubes.

In heat exchangers which operate at a high temperature, the temperature of the tube sheet to which the outer tubes are mounted will be very high because the secondary fluid when flowing through the tube sheet, has received all of the heat it will receive from the primary fluid.

A practical example of such a heat exchanger is one which receives heat from a primary fluid which is lithium, molten salt or liquid sodium. Such a heat exchanger is likely to have vertically extending bayonet tubes so that the main tube sheet which supports the outer tube is likely to be lower than the one which supports the inner tubes and is closer to the primary fluid.

High temperatures in the area of the connection between the outer tubes and the main tube sheet can be problematic where there is an abrupt discontinuation of the flow of liquid sodium coming into the heat exchanger. The temperature in the critical area will change within a very short time. When the temperature drops over a large range abruptly, components which are affected by the change can fail. For instance, if the main tube sheet should suddenly cool, it could become detached from the outer tube because of shrinkage.

Even without abrupt temperature drops, high temperatures in the area of the outer tube and main tube sheet are undesirable because of limitation on the life of the adjacent components due to creep. Changes in the relative dimensions of components in the area of the main tube sheet even when gradual are undesirable because tight fits are necessary for safe and efficient operation.

SUMMARY OF THE INVENTION

It is an object of the present invention to overcome drawbacks found in the prior art, such as those discussed above. Accordingly, a bayonet tube type heat exchanger having bayonet tube assemblies, each with an outer tube closed at one end and fitted a main tube sheet at the other end and a coaxial inner tube open at both ends, is provided with means to flow the heated secondary fluid through the main tube sheet through a conduit inside of and spaced from the outer tube.

BRIEF DESCRIPTION OF THE DRAWING

FIG. 1 is a view partly in section showing a bayonet

tube made in accordance with the present invention; and

FIG. 2 is a view in section substantially along the line 2-2 of FIG. 1.

DETAILED DESCRIPTION OF THE DRAWING

The drawing shows a bayonet tube assembly 10 which is connected at its upper end 12 to a downwardly projecting spigot 14 on the lower side of a main tube sheet 16.

The bayonet tube assembly 10 is one of many, each of which is attached to a spigot like the one 14 but only one is shown and described in detail since they are all similar in design and function. The bayonet tube assembly 10 is heated by a primary fluid which flows over it and each of the other bayonet tubes.

The secondary fluid, that is the fluid to be heated, flows down through the bayonet tube assembly 10 through an inner tube 18 which may be of double wall construction over most of its length, as shown. The fluid flows down through the inner tube 18 until it reaches the end of the tube. The bayonet tube assembly includes an outer tube 20 which is closed at its lower end 22 and the inner tube 18 is positioned within the outer tube 20 so that after the secondary fluid has flowed through the inner tube 18, it impinges against the lower end 22 of the outer tube 20 to reverse its direction and flow upwardly in the annular space between the inner 18 and the outer tube 20. The double wall construction of the inner tube 18 prevents the transfer of heat from the secondary fluid flowing upwardly between the inner tube 18 and the outer tube 20 and the cooler secondary fluid flowing downwardly through the inner tube 18.

In order to prevent the transfer of heat from the hot secondary fluid flowing upwardly in the bayonet tube assembly 10 to the tube sheet 16, an inner conduit 26 is provided. The inner conduit 26 has a lower end 28 which is located at a level below the main tube sheet 16 so that secondary fluid flowing upwardly between the inner tube 18 and the outer tube 20 will enter the inner conduit 26 and flow through that conduit as the secondary fluid passes through the main tube sheet 16. As shown in FIG. 2, the inner conduit 26 has a somewhat moon-shaped cross-section so that the available space in the outer tube 20 can be used effectively. The inner conduit 26 extends above the tube sheet 16 and is connected to a header pipe 30 which extends horizontally and which connects with other inner conduits to pick up hot secondary fluid coming out of the various bayonet tube assemblies in the heat exchanger. The header pipe 30 is connected with one or more feeder pipes 32, which pass through a secondary tube sheet 34.

The inner tube 18 extends centrally through the outer tube 20 over most of its length but in the portion of the bayonet tube 20 between the lower end 28 of the inner conduit 26 and the top of the main tube sheet 16 is set off to the side of the bayonet tube assembly as shown in FIG. 2.

The inner tube 18 and inner conduit 26 are surrounded with stagnant secondary fluid. The fluid does not move because the space between the main tube sheet 16 and the secondary tube sheet 34 is sealed as by wall 35.

The inner tube 18 is connected to a header pipe 36 which supplies fluid to other inner tubes. The header

pipes 36 are fed fluid through the feeder pipes 38 which pass through the secondary tube sheet 34.

In order to keep the secondary fluid which has not been heated and which must pass through the inner tubes 18 separated from the secondary fluid which has already been heated, a division wall 40 is provided. The feeder pipes 38 communicate with the space above the secondary tube sheet 34 to one side of the division wall 40 whereas the feeder pipes 32 communicate with the space above the tube sheet 34 to the other side of the division wall 40.

With the present invention, there will be no excessive heating of the tube sheet 16 because the heated secondary fluid will not transfer any considerable amount of heat to the tube sheet because it passes through the inner conduit 26 which does not contact the outer tube 20 in the vicinity of the tube sheet 16. Thus, the tube sheet 16 will not be weakened because of high temperatures and a sudden discontinuance of hot primary fluid resulting in a sudden drop in the temperature of the secondary fluid passing upwardly from the bayonet tube assembly 10 will not result in shock to the upper tube sheet 16 because the secondary fluid does not transfer heat to any great extent to the tube sheet 16 as it passes through it.

The foregoing describes but one preferred embodiment of the present invention, other embodiments being possible without exceeding the scope of the present invention as defined in the following claims.

What is claimed is:

1. A bayonet tube assembly comprising:
an outer tube being a closed end and an open end adapted to be connected to a tube sheet;
an inner tube within said outer tube, having an open end adjacent to said closed end of said outer tube, and being longer than said outer tube so that when said outer tube is connected to said tube sheet, said inner tube will extend through said tube sheet;
an inner conduit within the space between said inner tube and said outer tube and located to extend

from a location between said tube sheet and said open end of said inner tube through said tube sheet whereby secondary fluid can be passed through said inner tube to reverse its direction and flow back between said inner tube and said outer tube until reaching said inner conduit and then flow through said conduit to pass through said tube sheet.

5 2. The bayonet tube assembly defined in claim 1 wherein said inner conduit is moon-shaped in cross-section.

10 3. A bayonet tube-type heat exchanger wherein secondary fluid flowing through a bayonet tube is heated by primary fluid flowing over said tube comprising:

a main tube sheet;
an outer tube having a closed end and an open end, said outer tube being connected to said tube sheet at said open end;
an inner tube within said outer tube, said inner tube having an open end adjacent to said closed end of said outer tube and extending through said tube sheet;
an inner conduit, of a length considerably less than said inner tube or said outer tube, within the space between said inner tube and said outer tube and extending through said main tube sheet;
the space within said outer tube not enclosed by said inner tube and said inner conduit being sealed to create a stagnant layer of secondary fluid when secondary fluid is flowed down said inner tube toward said closed end of said outer tube to reverse its direction and flow back between the inner and outer tubes and then through said inner conduit and said main tube sheet.

25 4. The bayonet tube heat exchanger defined in claim 3 further comprising a secondary tube sheet, a division wall separating the space above said secondary tube sheet into two chambers, the inner tubes communicating with one of said chambers, the inner conduit communicating with the other of said chambers.
